ALBERT G. HEINLE AND ALBERT W. HEINLE, OF CRAFTON, PENNSYLVANIA.

METHOD OF AND APPARATUS FOR MAKING TAPERED DISKS.

Application filed March 30, 1920. Serial No. 370,027.

- Figure 1 is a plan view showing one form of finishing rolls in accordance with the present invention, and the table or support which cooperates therewith, and
- 5 Figure 2 is a plan view of a finished disk. Our invention has relation to the manufacture of tapered disks, such as are used in making vehicle wheels, coulters, and for various other purposes.
- 10 Our invention is designed to provide a simple and practical method by which tapered disks may be readily and accurately formed by the use of roll apparatus of simple character.
- 15 A further object of our invention is to provide a method of this character by which the tapering may be effected with a minimum distortion of the grain or fibres of the metal and without destroying the original 20 surfaces of the plates.
- Our invention also provides apparatus of simple and practical character for use in connection with the improved method.
- In the manufacture of a tapered disk in accordance with our invention, we provide a blank which is preferably generally circular, although it may be of polygonal form approximating a circle. This blank we subject to tapering and finishing operations which are preferably carried out by means of tapered overhung finishing rolls 11 and 12. In subjecting the disk to the action of these rolls, it is placed upon a suitable table or support 13, such as shown in 25 Figure 1. For this purpose the blank, at the time it is originally formed, is provided with a central opening *a* which may be slipped over a pin 14 on said support and thereby centered. The support 13 is pivoted, at 15, at one side of the longitudinal line of the finishing rolls 11 and 12, and is provided with a handle portion 16 extending to the opposite side of such center line. Any suitable means, such as the bars 17 and 30 17^a, may be provided for carrying this table or support. The latter is cut away at one side, as indicated at 18, in order to enable the disk thereon to be acted upon by said rolls. The table or support is so arranged that its 35 center post or pin 14 is at a distance to that side of the center line of the rolls 11 and 12 which is farthest from the center 15.
- The disk is placed upon this table support in the manner shown in Figure 1, and is 40 inserted to the action of the rolls 11 and 12.
- Owing to the position of the center 15 with respect to the center line of the rolls 11 and 12, it will be seen that the disk is first gripped between said rolls at its peripheral portion, and in a manner to cause the disk to be rotated about the pin 14. In this manner, the rolls rotate said disk to their action, thereby imparting the desired complete finish to the surfaces thereof.
- While we have shown the rolls 11 and 12 as being driven from the same pinion housing as the rolls 2 and 3, it will be obvious that these rolls may be driven in any suitable manner. They may be provided with the usual screw-down mechanism by which the distance between their centers may be varied to suit different thicknesses of the disks. As indicated in Figure 1, we preferably make the centers 14 and 15 adjustable by means of the slots 14^a and 15^a to also adapt said rolls and the table or support to disks of different diameters.
- The advantages of our invention will be apparent to those skilled in this art, since it provides a method of forming tapered disks which eliminates any cutting away of the surface of the disks, or the destruction of the original rolled surfaces thereof; and in which the distortion of the grains or fibres of the metal is reduced to a minimum.
- We do not desire to limit ourselves to the particular apparatus which we have herein shown and described, as it will be apparent to those familiar with this art that the radial stretching and tapering operations may be carried out with other forms of apparatus, as may also be the finishing operations.
- We claim:
1. Apparatus for forming tapered disks, comprising a pair of tapered overhung finishing rolls for rolling a disk into tapered form and a movable disk support for cooperation with said rolls, said support having means for centering a disk thereon in a position at one side of the longitudinal center line of the rolls, said support being pivoted at the opposite side of said center line, said support and the pivot point being spaced a distance at least equal to one-half the diameter of the disk to be rolled.
2. Apparatus for forming tapered disks, comprising a pair of tapered overhung finishing rolls for rolling a disk into tapered form and a movable disk support for cooperation with said rolls, said support hav-

ing means for centering a disk thereon in a position at one side of the longitudinal center line of the rolls, said support being pivoted at the opposite side of said center line, together with means located entirely at one side of the longitudinal center line of the rolls whereby said support may be shifted relatively to the rolls in the direction of the longitudinal axes of said rolls.

10. 3. Apparatus for forming tapered disks, comprising a pair of tapered overhung finishing rolls for rolling a disk into tapered form, a movable disk support cooperating with said rolls, said support having means for centering a disk thereon in a position at one side of the longitudinal center line of the rolls, said centering means being movable transversely with respect to the center line of the rolls and without movement of 15 said support, and a pivotal mounting for said support on the opposite side of the center line of said rolls from said centering means, substantially as described.

4. Apparatus for forming tapered disks, 20 comprising a pair of tapered overhung rolls, a disk support for cooperation with said rolls, a center on said support for centering a disk in position on said support, means for moving said support to produce a bite on the 25 disk along the line of a chord of said disk, and means for moving said support about a center entirely outside of the periphery of a supported disk to advance the center of the disk progressively into the line of 30 bite, substantially as described.

5. Apparatus for forming tapered disks, 35 comprising a pair of tapered overhung rolls for rolling a disk into tapered form, a disk support for cooperation with said rolls, a 40 pivotal mounting for said disk support, a center on said support, and means for moving said support to cause said center to move along an arc of a circle extending about said pivotal mounting and intersecting 45 the plane containing the axes of rotation of the rolls at the point of maximum bite of the rolls, substantially as described.

6. Apparatus for forming tapered disks, 50 comprising a pair of tapered overhung rolls for rolling a disk into tapered form, a disk support for cooperation with said rolls, a pivotal mounting for said disk at one side of the center line of the rolls support, a center on said support, and means for moving 55 said support to cause said center to progressively approach the line of bite of the rolls, the path of movement of said center being uniform and intersecting the line of bite of the rolls, substantially as de- 60 scribed.

7. Apparatus for forming tapered disks, 65 comprising a pair of tapered overhung rolls for rolling a disk into tapered form, a disk support for cooperation with said rolls, a pivotal mounting for said disk support lo-

cated on one side of the longitudinal axes of said rolls and outside of the periphery of the disk to be rolled, a center on said support located on the opposite side of the longitudinal axes of said rolls from said 70 pivotal mounting, and means for moving said support to cause said center to progressively approach the line of bite of said rolls, substantially as described.

8. The method of forming tapered disks 75 by rolling, comprising forming a circular blank, mounting the blank about a center, supporting said center for cooperation with the rolls, moving said center to cause the rolls to bite the blank along a chordal line 80 of the blank, and then moving said center to advance the center along a curved line which joins the opposite ends of a line radiating from said center and extending parallel to the radius of the blank which has 85 its outer end intersecting said chordal line at the periphery of the blank, substantially as described.

9. The method of forming tapered disks 90 by rolling, comprising forming a circular blank, mounting said blank about a center, supporting said center for cooperation with the rolls, moving said center to cause the rolls to bite along a chordal line of the blank, and then moving the center along a curved line which joins the opposite ends of a line radiating from said center and extending parallel to the radius of the blank which has 95 its outer end intersecting said chordal line at the periphery of the blank to advance 100 the same progressively into the line of bite of the rolls and axially thereof, substantially as described.

10. Apparatus for forming tapered disks, 105 comprising a pair of tapered overhung rolls for rolling disks into tapered form, and a movable disk support for cooperation with said rolls, said support having means for centering a disk thereon in a position at one side of the longitudinal center line of the 110 rolls and being pivoted at the opposite side of said center line outside of the periphery of a disk to be rolled, said rolls being constructed to permit the periphery of the disk being rolled to extend between the rolls and 115 beyond the line of bite thereof, substantially as described.

11. In an apparatus for rolling tapered disks, a pair of overhung rolls adapted to extend over a substantial portion of a disk and produce a bite at all times along a line at one side of the center of the disk, means for advancing the disk along an arcuate line into the line of bite of said rolls, said means being adapted to hold the disk with a portion of its periphery extending a greater distance lengthwise the rolls than the portion of the periphery where the line of bite intersects the periphery thereof, substantially as described.

12. In an apparatus for rolling tapered disks, a pair of overhung rolls, means for advancing the disk to be rolled along an arcuate line into the line of bite of said rolls, said means being adapted to hold the disk with a portion of its periphery extending a greater distance lengthwise of the rolls than the portion of the periphery where the line of bite intersects the periphery thereof, whereby the rolls automatically draw the disk into the line of bite, substantially as described.

13. In an apparatus for rolling tapered disks, a pair of overhung rolls, means for advancing the disk to be rolled along an arcuate line into the line of bite of said rolls, said means being adapted to hold the disk with a portion of its periphery extending a greater distance lengthwise of the rolls than the portion of the periphery where the

line of bite intersects the periphery thereof, 20 substantially as described.

14. In an apparatus for rolling tapered disks, a pair of overhung rolls, means pivotally mounted at one side of the center line of the rolls for advancing the disk to be rolled into the line of bite of said rolls along an arcuate path intersecting the line of bite of the rolls to cause the rolls to bite the disk along the line of a chord thereof, said means being adapted to hold the disk with its center on 25 one side of the center line of the rolls whereby the rolls automatically draw the disk into the bite thereof, substantially as described.

In testimony whereof, we have hereunto 30 set our hands.

ALBERT G. HEINLE.

ALBERT W. HEINLE.
